CLAIM

The ornamental design for a cover for a tow hook, as shown and described.

DESCRIPTION

FIG. 1 is a perspective view of our new design for a cover for tow hook;

FIG. 2 is a left side elevation view thereof;

FIG. 3 is a right-side elevation view thereof;

FIG. 4 is a front elevation view thereof;

FIG. 5 is a rear elevation view thereof;

FIG. 6 is a bottom view thereof;

FIG. 7 is a top view thereof; and

FIG. 8 is a cross-sectional view from the sight lines in FIG. 1; and,

FIG. 9 is a cross-sectional view from the sight lines in FIG. 1.

The broken lines shown in the drawing views are included for the purpose of showing environmental structure that forms no part of the claimed design.
